App.

UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

TANK VALVE.

Application filed May 14, 1923. Serial No. 638,795.

- This invention relates to rubber outlet valves for flush tanks and its object is to provide a removable type of connection between the rubber valve body and the metal lifting rod or stem, such connection being of a detachable character adapted to be manufactured at a low cost and capable of being readily applied to and removed from the rubber valve body.
- 10 Of the accompanying drawings, Fig. 1 is a vertical, sectional view showing a full-molded mushroom type of tank valve provided with my improved connection.
- Fig. 2 is a similar view showing a blown type of valve provided with a modified form of the invention.
- Fig. 3 is a vertical section showing another form of molded valve provided with a further modification of my invention.
- 20 Fig. 4 is a fragmental perspective view showing still another form of my invention.
- Referring at first to Fig. 1, 10 is a soft-rubber valve body of the mushroom type, to the general form of which no specific claim is here made, said body comprising a cylindroidal stem or upper portion 11, a conoidal lower seating portion or head 12 forming at its junction with said stem an annular wall part 13 of maximum thickness 30 at or adjacent to the seating zone of the head, and a flaring flange 14 forming an upward extension of the head to take in a wide range of outlet pipe diameters, there being a relatively wide mouth or opening 35 in the lower end for the removal of the core or mandrel which forms the central air chamber 16.
- The outlet pipe 17, having a valve seat 18, is shown in broken lines.
- 40 The universal practice heretofore, so far as I am aware, has been to embed in the top of the tank valve a metal block or "spud", usually of brass, having a screw-threaded aperture for the reception of the lifting rod, this spud being vulcanized to the rubber valve body and forming a permanent structure therewith. According to my present invention, I discard this practice and mold the top wall 19 of the valve body with a central aperture 20 through which, after removing the valve from its vulcanizing mold, is forced a metallic member 21 shaped somewhat like a collar button with a relatively-broad inner flange or base 22, a
- rounded outer head 23 of somewhat smaller 55 diameter, and a reduced connecting stem or neck 24, this button being centrally apertured from its upper end with a screw-threaded socket 25 for the reception of the screw-threaded lower end of the lifting stem 60 26. All parts of the button 21 and its aperture 20 are preferably of circular outline in plan. The length of the stem 24 is about the same as the normal thickness of the rubber wall 19. The aperture 20 is immediately surrounded with inner and outer button-seating surfaces 27, 28, and is made normally somewhat smaller in diameter than the stem 24—for example, the aperture may be $\frac{3}{16}$ of an inch and the button stem $\frac{3}{32}$ of 65 an inch in diameter—so that the rubber surrounding the stem is stretched and held under compression when the button is in place, and a water-tight joint is thereby effected, the displaced rubber causing the 70 wall 19 to bulge slightly around the edges of the heads 22, 23.
- In applying the button 21 to the rubber valve-body, it may be inserted either from above or below (somewhat more easily from below), and can be lubricated by wetting it to facilitate this operation, the rubber stretching to enlarge the aperture 20 when the top or bottom head (as the case may be) of the button passes through, and then snapping back to form a strong grip upon the button.
- 75 In Fig. 2, I have shown a valve body 10^a of the blown type, having a conical, thick-walled, soft-rubber upper portion 11^a, and a hemispherical, thin-walled soft-rubber lower or seating portion 12^a, united at its upper edge in a vulcanized seam with said upper portion, the latter being molded with a central aperture 20^a in which is inserted a modified form of metal button 21^a having a flanged, conical lower end, base, or head 22^a, a rounded upper end or head 23^a, and a relatively-long connecting stem or neck 24^a to take in the central wall thickness at the top of the valve body between the button-seating faces 27^a, 28^a, and hold the rubber under sealing compression by reason of the greater diameter of the button stem as compared with the normal diameter of the aperture. This type of button may conveniently be inserted and removed from above.
- 100 The above-described detachable buttons

21 and 21^a may be cheaply made in large quantities by any suitable manufacturing process such as die casting from molten metal or turning from a rod in a screw machine.

By employing a detachable connection of this type the manufacture of the valve body is somewhat simplified and when the valve has to be renewed in a flush tank it is possible to use the same button over again, thereby making it feasible to reduce the cost to the user after his tanks are once equipped.

It will be noted that in both of the forms above described there is a deformable, soft-rubber socket member on the valve, formed by the margins or wall structure surrounding the opening or mouth 20 or 20^a, said socket in these instances being open at both ends, while the complementary coupling member or button is detachable from the lifting rod and has two heads adapted to embrace said margins between them in the coupled condition of the parts.

25 In the modification, Fig. 3, 10^b is a soft-rubber, full-molded valve having a socket member formed by the margins of an aperture 20^b and closed at its lower end by an imperforate rubber wall 29, there being a pocket 30 under said aperture for the reception of a button 21^b consisting of a single flange or head formed integrally with the lower end of the lifting rod 26^b, said rod being coupled with and uncoupled from the valve by forcing the head 21^b through the aperture 20^b.

In the further modification shown in Fig. 4, the lifting rod 26^c is formed with a spring collar clip 31 embracing the neck of a soft-rubber button 32 formed on the upper end of the valve, both members of the coupling in this instance being yieldable to facilitate their connection and disconnection.

It will be understood that the precise form of embodiment may be further varied from the forms described without departing from the scope of my invention.

I claim:

50 1. In a flush-tank outlet-valve structure, the combination of a buoyant valve provided at its upper end with deformable, soft-rubber attaching means, and a lifting stem having complementary attaching means adapted

for detachable inter-engagement with said means on the valve.

55

2. In a flush-tank outlet-valve structure, the combination of a lifting stem and a buoyant valve having a detachable head and socket connection, one member of which is deformable and adapted to be coupled with and uncoupled at will from the other member by a relative axial movement of the two.

3. In a flush-tank outlet-valve structure, the combination of a buoyant valve having a flexible-mouthed, soft-rubber socket member 65 at its upper end, and a button detachably connected with the lower end of said stem and formed with two heads adapted to embrace the margin of said socket member between them and to be repeatedly forced into 70 and out of position in the mouth of said member to couple it with and uncouple it at will from the latter.

4. A flush-tank outlet-valve comprising a hollow, soft-rubber valve body centrally formed with a through aperture at its upper end, and a metal button detachably assembled with said valve body and formed with heads at its two ends and a connecting stem larger in diameter than the normal diameter 80 of said aperture.

5. A flush-tank outlet-valve comprising a soft-rubber, hollow valve body formed with a stretchable central through aperture at its upper end, and a metal button detachably 85 assembled with said valve body and formed with a screw-threaded socket for the reception of the threaded end of the lifting rod, said button having heads at its two ends, of which one is adapted to pass through 90 said aperture by stretching the latter, and an integral connecting stem larger in diameter than the normal diameter of said aperture for holding the rubber wall immediately surrounding said aperture under tight compression between said heads.

6. A hollow, buoyant valve body for flush tanks, said body including a soft-rubber upper part formed with a stretchable, through opening for the passage of a detachable connection, and inner and outer seats immediately surrounding said opening for sealing engagement with said connection.

In witness whereof I have hereunto set my hand this 5th day of May, 1923.

JOHN R. GAMMETER.
